UNITED STATES PATENT OFFICE.

GRANVILLE E. CHAMPLIN, OF LAUREL, NEBRASKA.

WEEDER.

SPECIFICATION forming part of Letters Patent No. 714,280, dated November 25, 1902.

Application filed March 8, 1902. Serial No. 97,329. (No model.)

To all whom it may concern:

Be it known that I, GRANVILLE E. CHAMPLIN, residing at Laurel, in the county of Cedar and State of Nebraska, have invented certain 5 useful Improvements in Weeders; and I do hereby declare that the following is a full, clear, and exact description of the invention, such as will enable others skilled in the art to which it appertains to make and use the same, reference being had to the accompanying drawings, which form a part of this specification.

This invention relates to a new and novel improvement in weeders, the object and nature of my invention being understood by all 15 those skilled in the art in the light of the accompanying drawings and descriptions.

Figure 1 shows a top view, with portions removed, of a weeder embodying my invention. Fig. 2 shows a side view of my weeder with a 20 portion broken away. Fig. 3 shows a rear view of the weeder-frame as detached, while Fig. 4 shows an end view of the supporting-axle as used in my invention.

My invention embodies, essentially, a supporting-axle C, a detail of which is shown in 25 Fig. 4, which is bent approximately A-shaped and provided below with the spindles c, adapted to receive the supporting-wheels 4. This axle below is strengthened by the transverse 30 bar 6, secured by means of the bolts 5. Secured to this axle C is a carrier-bar A, which is secured to the highest portion of the axle C by means of the bolt 2, as is disclosed in Fig. 2. The bolt 2, which passes through the 35 upper portion of the axle C, is also used to secure the toothed rack-bar E, which is additionally secured by means of the bolt 3, as disclosed in Fig. 2. This carrier-bar in the rear is provided with a suitable operator-seat 40 B, secured by the bolt 1, as is disclosed in Fig. 1, the operator in riding upon this weeder placing his feet either upon the transverse bar 6 or upon the spindles c. At its forward 45 end this carrier-bar A is provided with an ear 34, while extending from near the forward end and secured by the bolts 9 are the two brace-bars D, which diverge from the carrier-bar and then extend parallel therewith a suitable distance and then curve downward and 50 are secured to the axle C by means of the bolts 5, which are also made, it will be seen,

to do service in supporting the transverse bar 6, as disclosed in Figs. 1 and 4. Approximately centrally and above this carrier-bar is provided with a suitable ear 10, below which 55 is revolubly held a transverse rock-shaft F, which rock-shaft is given further support by means of the bearings 7, which are provided with downwardly-extending ears 8, which stride the brace-bars D and are secured by 60 means of a suitable pivot a to the adjacent brace-bar D, as disclosed in Fig. 2. At each end this rock-shaft F is provided with a forwardly-extending hanger 15, from which depends a chain 16, while approximately 65 centrally this rock-shaft is provided with the lever 13, which is adapted to work adjacent to the toothed rack-bar E, so that said lever is normally in engagement with said toothed rack-bar and locked behind one of the teeth 70 of the same. By this means the rock-shaft F may be adjustably held in any suitable position.

Pivots secured below the carrier-bar A is a tongue I, which tongue is provided with an upwardly-extending hook 35, engaging the ear 34, so that the tongue I is removably secured to the carrier-bar A. This tongue I extends forward a suitable distance and is provided with the usual neck-yoke and upon 80 the rear has secured to it two transverse frame-bars H H, positioned a suitable distance apart, as is disclosed in top view in Fig. 1, and these bars are held by means of the bolts 39, one of which is shown in detail 85 in Fig. 3. These bars extend outward a suitable distance and at each end support a rocking tooth-frame, to which are secured gangs of weeder-teeth b. These teeth are arranged in staggered relation, as shown. 90

At the end each transverse frame-bar H is provided with a bolt 20, and loosely working about the ends of these transverse frame-bars is a swinging yoke, comprising the lower horizontal member 18, provided at each end with 95 a loop 19 to encompass the ends of the transverse frame-bars, as is disclosed in Fig. 2, the bolt 20 acting as a horizontal pivot for this yoke 18. Secured below to each yoke are the transverse angle-bars 21, 23, and 25, which are strengthened by means of the transverse bars 24 24, as disclosed in Fig. 1. From these 100

angle-bars 21, 23, and 25 curve horizontally rearward and then vertically downward a plurality of spring-teeth *b*, which are made of wide flat material, such as steel, and have 5 their lower ends formed into four-cornered spike-shaped terminations *e*, as is disclosed in Fig. 2, one sharp edge of each tooth *e* being presented to the forward advance of the machine. To prevent these rocking tooth- 10 frames from racking or rocking sidewise, I secure to said member 21 at each end a cross member or bar 24, which bar is then carried backward and upward and secured, preferably, to the bolt 20, securing one end of the 15 yoke, while extending from the rear or last bar 25 and the end bar 24 is a second strengthening-rod 36, carried forward and upward and in turn secured to the bolt 20, supporting the yoke at its forward end. The hanger- 20 chains 16 are next secured to a suitable eyelet 17, referring now to Fig. 2, preferably fixed to the horizontal yoke member 18, so that the tongue is held suspended, approximately centrally, by means of the hook and 25 eye 35 and 34, while the rear end supporting the tooth-gangs is held by means of the chain 16, which is secured to the hanger 15 and shaft F, which shaft in turn is locked in a suitable position by means of the lever 13, so 30 that the teeth can be raised or lowered by means of this lever 13.

Secured to the forward transverse frame-bar H are the staples *x*, from which extend suitable pulleys or sheaves *z*, over which 35 passes a chain W, secured centrally by means of the bar *g*, and to the end of each chain is secured a singletree *h*, as is shown in Fig. 1. From this it will be noticed that I provide, first, a sulky-frame, comprising the trans- 40 verse shaft F and the carrier-bar A, to which is detachably and adjustably secured the tongue carrying the teeth-gangs, as disclosed.

To the frame is further permitted a rocking movement in a vertical plane, while the 45 whole of the teeth-frames may be raised and lowered.

In Fig. 3 I have shown the location of the strengthening-rods 36 and 31 in connection with the bolts 20 and 32, secured to the trans- 50 verse members H in supporting the same. Brace rods or bars 30 are attached at one end to the bar A and at their opposite ends to members H.

Having thus described my said invention,

what I claim as new, and desire to secure by 55 United States Letters Patent, is—

1. In a weeder, the combination with a wheel-supported carrier-bar, a rock-shaft secured to said carrier-bar, a tongue movably secured to the forward end of said carrier- 60 bar, transverse frame-bars secured to the rear end of said tongue, pivotally-held yokes secured to the ends of said transverse frame-bars, toothed bars secured to said yokes, a plurality of rearwardly and downwardly curv- 65 ing teeth secured to each of said toothed bars, and means to connect said toothed bars to aforesaid rock-shaft, as and for the purpose set forth.

2. The combination with an approximately 70 A-shaped supporting-frame provided with two supporting-wheels, a carrier-bar secured to the uppermost end of said supporting-frame, an operator-seat at the rear end of said carrier-bar, an eyelet at the forward end 75 of said carrier-bar, brace-bars curving upward and inward, extending from aforesaid supporting-frame and being secured to the forward end of said carrier-bar, a rock-shaft, bearings supporting said rock-shaft secured 80 to aforesaid carrier-bar and to said brace-bars, an adjusting-lever secured to said rock-shaft, terminal hangers extending from said rock-shaft provided with depending chains, a tongue pivotally secured near one end to 85 the ear of said carrier-bar, two transverse frame-bars secured to the rear end of said tongue, a pivotally-held yoke secured to the ends of said frame-bars, a plurality of angle-bars secured to said yokes, a plurality of 90 rearwardly and downwardly curving teeth secured to each of said angle-bars, said teeth being in a staggered position, aforesaid chains being connected to said yokes all arranged, so that said angle-bars will be permitted a 95 rocking movement in a vertical plane at right angles to the chains of the machine, said frame members supporting aforesaid teeth being permitted upward and downward adjustment by virtue of said rock-shaft, as has 100 been set forth.

In testimony whereof I have affixed my signature in presence of two witnesses.

GRANVILLE E. CHAMPLIN.
